United States Patent Office

Des. 196,149
Patented Aug. 27, 1963

196,149

BOTTLE

Robert H. Knies, Manheim Township, Lancaster County, Pa., assignor to Armstrong Cork Company, Lancaster, Pa., a corporation of Pennsylvania

Filed July 9, 1962, Ser. No. 70,836

Term of patent 14 years

(Cl. D58—8)

FIGURE 3 is a fragmentary developed plan view of one-half of the decorative band, the other half being substantially the same.

I claim:

The ornamental design for a bottle, substantially as shown and described.
